GEORG GRÄBE, OF NIKOLASSEE, NEAR BERLIN, GERMANY, ASSIGNOR TO SIEMENS & HALSKE AKTIENGESELLSCHAFT, OF BERLIN, GERMANY, A CORPORATION OF GERMANY.

APPARATUS FOR METERING CONVERSATIONS IN AUTOMATIC TELEPHONE SYSTEMS.

1,107,290.

Specification of Letters Patent. Patented Aug. 18, 1914.

Application filed June 24, 1911. Serial No. 635,202.

To all whom it may concern:

Be it known that I, GEORG GRÄBE, a subject of the German Emperor, residing at Nikolassee, near Berlin, Germany, have invented certain new and useful Improvements in Apparatus for Metering Conversations in Automatic Telephone Systems, of which the following is a specification.

This invention relates to apparatus for metering conversations in automatic telephone systems, in which the metering takes place after the termination of a conversation.

According to the invention the meter of the calling subscriber is connected in circuit by one or more retarding relays which, when the automatic switches are released after the termination of a conversation, temporarily connect the meter in circuit.

In arrangements comprising line switches or pre-selectors, selectors and connectors, in which a cut-off relay at the pre-selector is energized as long as the connection lasts, according to the invention when the pre-selector is adjusted, a second relay in addition to the testing or cut-off relay is energized, the arrangement being such that these two relays allow their armatures to fall at different speeds, and the meter circuit is closed in the interval resulting owing to the armatures of the two relays falling at different speeds.

The cut-off relay is rendered currentless, as is requisite for breaking the connection in the pre-selector, in a manner known heretofore by means of a temporary interruption of the holding current flowing by way of the private or third line. In order to negative the holding current at the pre-selector for a sufficiently long time, for the purpose of releasing the pre-selector, during which time both the cut-off relay and also the retarding relay in the pre-selector may be currentless, according to the invention I provide in the selector an additional relay which, when the selector is released, keeps the third line leading to the pre-selector interrupted for a sufficiently long time. This action is obtained by temporarily connecting a high resistance relay into the third line at the selector leading to the pre-selector during the release of the selector, in order to negative the action of the holding current in the relay of the pre-selector. The current which in this

case still remains in the third line suffices, however, for energizing this relay which holds itself connected to the line until the latter is interrupted at the pre-selector.

In arrangements in which the selectors are released by the called subscriber or when the required line is engaged, the first selector and the preselector of the calling subscriber is to be released only when the calling subscriber has replaced his receiver. According to the invention when an adjusted first selector is released the holding current flowing in the third line leading to the pre-selector is first interrupted for a short time. Subsequently, after the circuit of the holding current has been closed, for a long time, the circuit for registering the finished conversation is closed by way of one or both of the branches of the talking line during the short interruption of the third line.

Figure 1 is a diagrammatical representation of a subscriber's station with its pre-selector and a first group selector; Fig. 2 represents diagrammatically the line connector; Fig. 3 is a side elevation, and Fig. 4 is a plan view of a control switch for the group selector.

A calling station T_1 is connected by way of the pre-selector VW , a selector GW and a connector LW , e. g. of the known Strowger type, with the called line a_2, b_3 .

In the drawing the selectors are shown in that position which they occupy during a conversation, only those parts of the connections and apparatus being shown, for the sake of clearness, which are requisite for understanding the invention.

When the calling subscriber lifts the receiver at the station T_1 , line branches a and b are connected at that station, whereby relay R at the preselector VW is energized by way of the subscriber's line, and the feeding magnet D_V of the preselector is thrown into operation. At the first stroke of this magnet head contacts k_1 and k_2 are opened and k_3 is closed. By opening k_1 the line of the caller is blocked. By the opening of k_2 and closing of k_3 relay D_V is connected with the battery G and rendered independent of electro-magnet R . The switch arm of the preselector VW now moves through the operation of D_V until a free line to the group selector GW is found. If the group selector is already occupied by another preselector

at line c_1 , relay T_r in the preselector VW does not receive sufficient current and therefore can not be sufficiently energized. On the other hand if the group selector GW is free then the current flows to the ground from the battery G by way of the contact r_1 , the coils 1 and 2 of the cut-off and testing relay T_r , switch lever o_3 , conductor c_1 , resistance w_1 , contacts h_1, n_2 , side switch lever 4 in position 1, coil 2 of the testing relay P and the side switch lever 5 in position 1. The relay T_r and P are hereby energized. While disconnecting the relay R the relay T_r connects the subscribers' lines a, b by way 15 of the contacts t_1, t_2 to the switch levers o_1, o_2 and the retarding relay V by way of the contact t_4 into a local holding circuit which is connected by the battery G by way of the contact t_4 and the coil of the relay V to ground. The relay V which is hereby energized prepares the circuit broken at the contact t_3 for the meter by closing its contact v_1 , breaks at contact v_2 the circuit for the rotary electromagnet D of the pre-selector VW , and at contact v_3 connects the coil 2 of the relay T_r by way of the head contact h_2 to the battery G .

At " v_2 " the high resistance winding tr_1 is short circuited by T_r whereby the pre-selector VW is occupied and the calling line blocked for any calls of other subscribers. Simultaneously the relay V interrupts at v_2 the circuit over relay D , so that the selector comes at rest with its arms o_1, o_2, o_3 , on line 25 a_1, b_1, c_1 . In the group selector GW the relays A and B are connected in position 1 to the calling line by way of the windings of differential relay X and the control arms 1, 2. The relays A and B attract their 30 armatures whereas X does not attract its armature. The energized relay P brings about the connection of the side switch electromagnet S by way of the contact p^1 to the interrupter U_1 , whereby the side switch is 35 brought into its second position. Now relay P is deenergized, whereas T_r is energized over arm 3. If now the subscriber at station T_r operates his selecting disk T_s , the circuit over a_2 is grounded whereby relay X is energized through the short circuiting 40 of relay B , whereby relay A remains energized. Relay X when energized closes a local circuit at w_1 for B , so that this relay is energized and keeps open at b_1 the circuit 45 for the releasing magnets M and N . During the operation of selecting disk T_s the circuit over conductor a is repeatedly interrupted, while the conductor b remains grounded, so that X and B remain energized. Now relay A is energized during this 50 impulse period, lifting magnet H_a receives current over contacts a_4 and w_2 and thereby lifts the shaft 50 of the group selector GW one step. At the first step head contacts b_1, h_2 are closed. By closing contact h_1 elec-

tro-magnet S is energized, whereas over h_2 a circuit is set for selector releasing magnet M and control switch magnet N . After the return of the selecting disk T_s the grounding of conductors a, b is interrupted by the disk 70 and A and B are again energized by the subscriber's line a, b relay X is deenergized and thereby opens the circuit relay S at w_2 so that the control switch arms, operated by N are moved into position 3. In this position 75 S is again energized by way of contact p_2 of solenoid P . Simultaneously a circuit for relay D is closed over control arm 5 by way of the fast rotating interrupter U_1 . Relay D receives current impulses and turns the 80 selecting arms of group selector GW , until they contact with the terminal lines a_2, b_2, c_2 , of a free line selector LW . The detail arrangement of the contact arms and their movement is illustrated in Figs. 3 and 4 85 and will be described hereinafter in detail.

In the positions 3—6 of the control switch arm 4 the testing relay P is connected with the testing arm of the group selector. When the line selector is occupied line c_2 is interrupted, because head contact h_4 is open and contact b_5 is opened on account of the energizing of the relay B_1 , relay P of the group selector therefore remains deenergized and thus the current for the magnet D 90 closed, so that the switch arms are continued to be operated. When the line selector is free, c_2 is connected to battery G through contacts of relay B_1 by way of w_2 , arm 16 in position 1, contact h_4 , back contact b_5 . Therefore relay P is energized when the testing arm of the group selector contacts with line c_2 . The relay P interrupts, when energized, the circuit in which magnet D is located, so that the selector arms remain at 100 position 3. In this latter position winding l is short circuited on magnet P by way of arm 5 whereby the current in P is increased. Simultaneously magnet S is directly connected with the interrupter U_1 when arm 105 6 is in the position 4, so that S is energized for a short moment and immediately deenergized whereby the control switch arms of the group selector are brought into position 5.

In the position 4—6 of arms 1—2 of the control switch, line a_1, b_1 , is connected with a_2, b_2 and A, B, X are disconnected from the calling line a, b . In place of these latter elements the relay A_1, B_1, X_1 of the line selector LW are connected with the calling line a, b . Relays A_1, B_1 are energized, X_1 is not energized. Relay B_1 disconnects at b_5 the battery G from c_2 and thereby renders the line selector occupied. Relay P of the group selector has been already deenergized 110

120

125

130

135

in the position 4 of the control switch of the group selector. Thus p_1 is already opened in position 5 and control magnet S remains deenergized. The group selector is therefore now in speaking position. If now subscriber T_1 again operates his numeral disk the two branches a and b are simultaneously grounded. Relays X_1 and A_1 are energized by way of a , b and relay B_1 is excited 5 by a local circuit by way of a contact x_4 . Relay X_1 closes at x_3 the circuit for magnet S_1 , which is thereby energized. When the numeral disk at the subscriber's station returns, the line b remains grounded, whereas 10 the current through a is interrupted a certain number of times corresponding with the number which the subscriber had previously selected. At each interruption relay A_1 is deenergized and closes thereby at a_5 the circuit for lifting magnet H_1 so that the shaft of the line selector is lifted a number 15 of steps corresponding with the numeral which had previously been selected. At the first lifting step h_1 is opened and h_2 closed. After h_1 is opened the line selector will be free to receive another call only after it has been returned into normal condition, which is done by the setting of a circuit over h_3 with the aid of relays M_1 and N_1 . After 20 the lifting impulses for magnet H_1 are given by the numeral disk lines a , b are disconnected from the ground so that together with relay A_1 also relay B_1 is energized by way of c_3 , b_1 , whereas relay X_1 is deenergized. 25 X_1 thereby interrupts the circuit for S_1 on account of its armature interrupting the circuit at x_3 , relay S_1 is deenergized and brings the control arms of the line selector into position 2. In this position now operating 30 magnet D_1 instead of lifting magnet H_1 is rendered dependent upon relay A_1 . If now the subscriber again operates his numeral disk, relay B_1 is first deenergized, whereby relay X_1 is energized and whereby a local 35 circuit for relay B_1 is closed, which latter consequently is energized. Simultaneously relay X_1 closes at x_3 the circuit for S_1 so that the latter relay is again energized. When the numeral switch returns to zero current 40 impulses are produced for relay A_1 , whereby operating magnet D_1 is actuated and the selecting arbor is turned until its arms make contact with the desired line. When the numeral disk has reached its resting position, 45 lines a , b are disconnected from the ground, relay X_1 drops its armature and interrupts the current for control magnet S_1 , so that the latter is again deenergized and shifts the control switch into position 3. In this position 50 relay Y is connected as a testing relay with the testing arm of LW .

If the desired line is otherwise occupied, the preselector of the latter has its contact k_1 (Fig. 1) open and therefore relay Y in 55 the line selector can not be energized. If

on the other hand the desired line is free then its preselector contact k_1 is closed so that battery G is connected over contact k_2 , windings tr_2 and tr_1 of T_r , and k at the preselector to line c_2 . Through this connection 70 relay Y is energized and connects relay S_1 with interrupter U_2 by means of contact y_1 so that relay S_1 is energized and deenergized by the interrupter whereby the control lever is brought on to the fourth contact. In this 75 position S_1 is connected directly with U_2 by way of arm 9, so that the control switch is moved to the fifth position. From the fifth position to and including the eighth position line c_3 is grounded directly by way of 80 arm 13 of the control switch by which the occupied condition of the desired line is maintained. Relay Y is then disconnected from line c_3 . At the moment the desired line is occupied (in case it was free) relay 85 T_r is connected with the preselector and thus relay R of this preselector disconnected from its subscriber line, so that the called subscriber now can not himself call. In the fourth position of the control switch of the 90 line selector arm 11 also closes a circuit for the ringing relay L , so that thereby the called subscriber is notified by an alarm.

In the fifth position of the arms the ringing relay L is connected with a switch P_s 95 which in certain time intervals, for instance ten seconds, temporarily closes its circuit and thus periodically energizes relay L which periodically continues calling the desired subscriber from the current source RQ . 100 If the called subscriber answers, that is, when he removes the receiver, the line a at his station is connected with b so that relay Y is energized (by way of relay Y , arms 13, 10, line b_3 , subscriber line a_3 , arm 12, choking coil DR , battery G). Relay Y interrupts at y_2 the circuit of relay L and further connects relay S_1 which operates the control switch, with U_2 , so that S_1 is continually energized and deenergized 105 whereby the control switch is brought into its sixth position, in which the circuit for relay S_1 is broken by B_1 and Y at contacts y_3 , b_0 . The line selector is now in condition 110 to permit speaking. In this talking position the relays A , B , X are disconnected from the lines a_1 , b_1 and the latter are connected with the lines a_2 , b_2 , the testing line c_2 being connected by way of the side switch levers 4 and 5 to the low resistance coil 2 of the testing relay P . The connector LW is adjusted in similar known manner to the required line a_3 , b_3 , its side switch S_1 being placed in the through position 7 after the called subscriber has been called and has 115 announced himself.

In the through position not only the relays A_1 , B_1 , X_1 , but also a relay Y and a choking coil D_r , by way of which the microphones of the stations of the subscribers 120

speaking to one another are fed with current, are connected to the two sides of the talking circuit divided by condensers in the connector. The line c_2 is interrupted at the connector LW.

5 When after the termination of the conversation the calling or called subscriber replaces his telephone, the relays A₁, B₁, X₁ and the relay Y becomes currentless and in 10 this manner the side switch electromagnet S₁ is connected by way of the contacts b₆ or y₃, side switch lever 9 to interrupter U₂, whereby the side switch magnet S₁ is energized and brings the said switch of 15 connector LW out of its sixth position into the seventh position. In this position the magnet S₁ is connected by way contacts b₆ or y₃, coil 1 of relay Q, side switch lever 9 of the side switch electromagnet S₁ to an 20 interrupter U₂, whereby the relay Q is energized and, simultaneously, the side switch electromagnet S₁ brings the side switch of the connector LW into position 8. When 25 the relay Q attracts its armature it closes the contacts q₁ and q₂ and opens the contact q₃.

Owing to the contact q₁ being closed the line a₂ is grounded and the metering circuit is made at the connector. Owing to the 30 contact q₂ being closed a current flows from the battery G by way of the contact q₂, coil 2 of the relay Q, resistance w₂, line c₂, side switch lever 4 of the selector GW in position 5, and relay P to ground. This relay 35 P is energized and connects in circuit the side switch electromagnet S by way of the side switch lever 6, the contact p₁ and the interrupter U₁, so that the side switch of the selector GW passes from the speaking 40 position 5 into position 6. In this position 6 the holding circuit of the relay T_r is temporarily interrupted in the line c₁ at the side switch lever 3. The cut-off relay T_r consequently lets its armature fall and the contact t₂ is closed. As the retarding relay V 45 holds its armature attracted for some time longer, however, as long as the side switch of the selector GW is located in position 6 the meter Z receives a current from the battery G by way of the contact t₂, meter Z, contact v₁, switch lever o₁, line a₁, side switch lever 1, line a₂, contact q₁ and the ground, and registration takes place. Further, in position 6 the side switch electromagnet S is directly connected with the interrupter U₁ and the side switch of the selector moves from position 6 into position 7, in which the circuit for the cut-off relay T_r is closed again at the switch lever 3, in order 55 that this relay T_r may be energized and the metering circuit broken at the contact t₂. The relays A, B, X are simultaneously connected again to the talking line and the relays Q and P are rendered currentless owing 60 to their circuit being broken at the side 65 connector LW.

switch lever 4. The relay Q releases its armature and closes the contact q₃. If the relay Y is currentless, that is to say if the called subscriber has already replaced his receiver, the releasing electromagnets M₁ 70 and N₁ of the connector are grounded in the following circuit: battery G, contacts q₃, y₂, side switch lever 8 (in position 8), releasing electromagnet N₁ and electromagnet M₁, head contact h₃, and ground, whereby 75 the connector and the side switch are returned into its rest position. In position 7 the side switch magnet S of the selector GW is likewise directly connected with the interrupter U₁, so that the side switch moves into position 8. If the relays A, B and X in position 7 are no longer energized, that is to say if the calling subscriber has already replaced his receiver, in the position 8 current flows from battery G by way of the side switch lever 7, contact b₄, releasing electromagnets M and N and the head contact h₂ to the ground. The releasing electromagnets M and N₁ are hereby energized and connect themselves by way of the contact n₁ 80 into a holding circuit which is maintained until the selector descends into its rest position and the head contact h₂ is consequently opened. Further, the releasing electromagnet N opens a contact n₂ whereby the high 85 resistance relay H which has hitherto been short-circuited is connected into the line c₁. The current thereby weakened in this line is not sufficient to maintain the excitation of the cut-off relay T_r. The sensitive relay H, 90 on the contrary, is energized by this current, and by attracting its armature opens the contact h₁ whereby the circuit remains interrupted by way of the contact n₂ even after the releasing electromagnet N has become currentless. The releasing relay T_r 95 now releases its armature and disconnects the holding circuit for the relay V. As the interruption is now permanent, the relay V also releases its armature and after the contact v₂ is closed, in consequence of the excitation of the rotary magnet D_v of the pre-selector VW by way of the contact v₂ of the relay V, the head contact h₀ and the interrupter U₁ the pre-selector returns into its 100 rest position. The contact levers o₁, o₂, o₃ of the pre-selector VW leave the contacts of the lines a₁, b₁, c₁ and the current in the relay H is interrupted. If the connection is 105 not made, for example if the line was engaged, the selectors are released in known manner. The operations at the selector GW and connector LW take place in the same manner as described above. As the relay Q is first switched into the through position 7, 110 however, the meter circuit is not closed at the contact q₁ and no metering takes place. 115

The form of the controlling switch which contains the sections 1 to 7 and 10 to 17 in the group selector and line selector, respe 120

tively, is shown in detail in Figs. 3 and 4. It comprises an actuating electromagnet S_1 , the armature 21 of which is connected through a tension spring 22 at yoke 23 of the frame. Armature 21 is pivoted at 24 and provided with an extension 25, which carries a detent 26, which abuts against the yoke and thus limits the motion of the armature in the direction of the tension of the spring. In the frame of the device is journaled a shaft 27, which carries a toothed segment 28 and a suitable number of switch arms 29. The extension 25 of armature 21 carries a pawl 30, which coöperates with the teeth of the segment 28. The frame of the apparatus also carries a spring pressed locking pawl 31, which also engages the teeth of the segment and normally prevents their movement in the direction of the arrow (Fig. 4). Adjacent to electromagnet S is disposed electromagnet N with its armature 34, pivoted at 34 a . This armature carries an extension 33 to which one end of spring 32 is attached, while the other end of this spring is attached to segment 28 in such manner that it tends to revolve this segment in the direction of the arrow after the segment has been previously moved opposite to the direction of the arrow. Each arm 29 coöperates with a suitable number of contact segments 35, which are located in the plane of rotation of the arm and which represent the contact points of the switches 1 to 7 and 10 to 17 in Figs. 1 and 2, respectively. In Fig. 3 the actual arrangement of the lever arms 29 and their corresponding segments 35 is shown whereas in Figs. 1 and 2 they are only diagrammatically illustrated and spread apart to show their connection in the wiring system. Armature 35 further carries at its outer end a bar 36, which carries at its free end two detents 37 and 38, which coöperate respectively with pawls 30 and 31.

The device operates as follows: If magnet S is energized pawl 30 is lifted from one tooth into the next one. If the magnet is deenergized armature 21 returns into its off position through the action of spring 22, and the segment 28, and with it shaft 27 is moved one tooth opposite to the direction of the arrow, so that thereby arms 29 are moved from the first contact 35 to the next. By this movement the several circuits connected with the groups 1 to 7 and 10 to 17 in Figs. 1 and 2 are opened or closed according to their connections with the contacts 35. If now for the return of the de-

vice to normal magnet N is energized by suitable circuit connection previously described with reference to Figs. 1 and 2, its armature 34 is attracted and pawl 36, with its detents 37 and 38, releases pawls 30 and 31 respectively from the teeth of segment 38, so that the latter through the action of spring 32 returns to its normal position in the direction of the arrow.

I claim:—

1. In an automatic telephone exchange comprising switches for interconnecting a calling line with a called line, the combination of a meter associated with the calling line, a quick acting relay and a slow acting relay energized during the conversation and deenergized at the end of the conversation, a meter circuit in dependence from the called subscriber's station and adapted to be closed momentarily at the end of the conversation when both of said relays are deenergized. 80
2. In an automatic telephone system comprising automatic switches for connecting a calling line with a called line, the combination of a pre-selector for connecting the calling line with an idle automatic switch, a meter in the pre-selector and connected to the calling line, a cut-off relay in the pre-selector and energized during the conversation, a retarding relay in the pre-selector and energized during the conversation, and a circuit for the meter closed by way of a working contact of the retarding relay and a rest contact of the cut-off relay. 85
3. In an automatic telephone system comprising a pre-selector, one or more selectors and a connector for connecting a calling line with a called line, the combination of a meter in the pre-selector and connected to the calling line, a cut-off relay in the pre-selector and energized during the conversation by a circuit closed by way of the first selector, means in the first selector for causing the said relay to release its armature, a retarding relay in the pre-selector and energized during the conversation, and a circuit for the meter closed by way of a working contact of the retarding relay and a rest contact of the cut-off relay. 95

In testimony whereof, I have signed my name to this specification in the presence of 110 two witnesses.

GEORG GRABE.
